UNITED STATES PATENT OFFICE

171,023

ATOMIZER OR SIMILAR ARTICLE

"D" Flavius Bacheller, Glendale, Calif.

Application December 9, 1952, Serial No. 22,609

Term of patent 7 years

(CL. D83—1)

To all whom it may concern:

Be it known that I, "D" Flavius Bacheller, a citizen of the United States, residing in Glendale, in the county of Los Angeles, State of California, have invented a new, original, and ornamental Design for an Atomizer or Similar Article, of which the following is a specification, reference being had to the accompanying drawing forming a part thereof.

Figure 1 is a side perspective view of an atomizer or similar article showing my new design.

Figure 2 is a side elevational view.

Figure 3 is a front elevational view.

The essential features of my design reside in the portions shown in full lines.

I claim:

The ornamental design for an atomizer or similar article, substantially as shown and described.

"D" FLAVIUS BACHELLER.
